UNITED STATES PATENT OFFICE.

JAMES LAYDEN, OF BROOKLYN, NEW YORK.

SHIRT AND NECKBAND CONSTRUCTION.

1,427,744.

Specification of Letters Patent. Patented Aug. 29, 1922.

Application filed May 14, 1921. Serial No. 469,513.

To all whom it may concern:

Be it known that I, JAMES LAYDEN, a citizen of the United States, residing at Brooklyn, in the county of Kings and State 5 of New York, have invented new and useful Improvements in Shirt and Neckband Constructions, of which the following is a specification.

This invention relates to the class of apparel and more particularly to shirt and neck band construction and is particularly designed for use in connection with my invention of collar holder shown in my co-pending application Serial Number 469514, 10 filed May 14, 1921, and the application of collar shown in my co-pending application Serial No. 469515, filed May 14, 1921.

The primary object of the invention is to provide a neck band construction which 20 will operate when the neck band is closed to prevent the formation of a bulge or obstruction at the joint between the ends of the band, the arrangement presenting a smooth or flat inner surface capable of adapting itself to the neck of the wearer with resulting comfort.

Another object of the invention is to provide a shirt and neck band construction which will eliminate the necessity of radially 30 projecting collar retaining buttons.

Another object of the invention is to provide a shirt and neck band construction in which the vertical edges of the shirt are joined to the neck band in a manner which 35 will allow the edges of the shirt to overlap at the front or across at such point, while holding the edges of the neck band flush with each other at the joint both as regards the inside surface of the neck band and 40 the outside surface or circumference of the neck band.

With the above and other objects in view which will appear as the nature of the invention is better understood, the same consists in the improved construction and novel arrangements of parts which will hereinafter be fully described and particularly pointed out in the claims.

In the accompanying drawing, has been 50 illustrated, a single and preferred form of the invention, it being, however, understood that no limitations are necessarily made to the precise structural details therein exhibited, but that changes, alterations and 55 modifications within the scope of the claims may be resorted to when desired.

Figure 1, is an edge view of the neck band and shirt constructed in accordance with my invention.

Figure 2 is a plan view of the neck band. 60

Figure 3 is a perspective view of the neck band showing the same opened.

Figure 4 is a perspective view of the neck band and shirt showing the same partly closed toward a normal position. 65

Figure 5 is a view similar to Figure 4 showing the neck band fully closed.

Figure 6 is a perspective view of the holder.

In carrying the invention into practice, 70 use is made of a neck band 10 formed from a single piece of material and provided with parallel edges A and B, an extension C at one end and a cutaway portion D at its opposite end. On said extension C are 75 formed foldable flaps 11, 11^a, 11^b and 11^c and on the transverse edges of the strip A at points to either side of said extension C are similar flaps 11^d and 11^e. The purpose of all of these flaps will be hereinafter explained. The cutaway portion D is defined by flaps 11^f, 11^g, 11^h, 11ⁱ, 11^j and 11^k, the flaps 11^j and 11^k conforming with the flaps 11^d and 11^e. The longitudinal edges A and B of this neck band are also formed with longitudinal flaps 11^l and 11^m. 80

Except for the front part, the shirt 12 is of ordinary construction. In the open front of the shirt I cut away a portion of the material as at 13 giving the same preferably an angular cut from the vertical edge 14 to its juncture with the edge of the neck band for a purpose to appear presently.

The neck band when cut as shown in Figure 2 is folded on itself along the medial line A', the marginal foldable flaps upon the edges of the material first being folded against the body of the material and stitched thereto. The blank then assumes the form 100 shown in Figure 3 and the same is stitched along its parallel edges A and B to the edge E at the neck of the shirt. The neck band of the material is then folded a second time along the longitudinal line B' and the folds 105 of the neck band then stitched together at B² and at B³, the latter arranged with its stitching broken at B⁴ so as to form a pocket at the back of the neck band and upon the external surface thereof, the same 110 adapted for the reception of a collar fastening (not shown). When the neck band

material is joined to the shirt as shown in Figure 3, the band is uniformly defined by two folds but when arranged as shown in Figure 4, it presents four folds inwardly 5 of the vertical edges of the open side of the shirt and two folds at the immediate ends of the neck band and also in proximity to the vertical edges of the shirt at the open side thereof. This produces flaps F and G 10 at the ends of the neck band which are adapted to overlap one another when the neck band is closed and thereby give the neck band a uniform four ply or four fold construction throughout its circumference, 15 eliminating the formation of any bulk at any point in the circumference of the neck band both inside and outside thereof. The construction also permits the edge 15 of the shirt to overlie the edge 14 and to extend 20 across the cutaway portion 13 when said neck band is closed. By cutting the shirt as shown and described at 13 and associating this construction with the flaps F and G an extremely neat and tidy appearance is 25 given to the shirt at the point of connection of the aforesaid neck band.

By forming the neck band as described, it will be observed that the ends of the band are open so as to accommodate the ends of 30 a holding device 16, the same having tongues 18-18 adapted to be passed through vertical slots 19-19 formed in said neck band. These tongues are adapted to be connected in slots formed in the ends of 35 the collar as shown and described in my aforesaid co-pending application for collar executed as of even date with this application.

While I have specifically referred to one 40 desired manner of cutting my neck band, I of course do not wish to be limited in this respect. I am particularly desirous of emphasizing the construction of a neck band which consists of a number of folds at its 45 immediate ends so that when the ends are brought together the combined number of folds in said ends will be equal to the folds in any other part of the neck band throughout the circumference thereof.

50 What is claimed as new is:—

1. A neck band formed with a multiplicity of folds, the folds at the ends of the band

being less in number than the folds in the body of the band and formed so that the ends may be overlapped whereby the combined number of folds in said ends will be equal to the number of folds in the body of said band, the said neck band having vertical slots therein arranged in parallel relation to the vertical edges of the ends of the 60 band.

2. A neck band provided with overlapping free ends formed so that the joint between the ends lies flush respectively with the inside and outside surfaces of the band 65 when the latter is closed.

3. A neck band provided with overlapping free ends formed so that the joint between the ends lies flush respectively with the inside and outside surfaces of the band 70 when the latter is closed, the said band having vertical slots formed therein adjacent to its ends, and a pocket formed in the band at the rear thereof.

4. A neck band provided with overlapping free ends formed so that the joint between the ends lies flush respectively with the inside and outside surfaces of the band when the latter is closed, the said band having vertical slots formed therein adjacent to 80 its ends, and a pocket formed in the rear of said band, said pocket opening in a downward direction, as and for the purpose specified.

5. A structure of the class described comprising, a shirt open at its front and provided with a diagonal cutaway portion, and a neck band secured to the shirt and having ends adapted to overlap each other, one of said ends extending into the plane of said 85 cutaway portion.

6. A structure of the class described comprising a shirt open at its front and provided with a diagonal cutaway portion, a neck band secured to the shirt and having 95 ends adapted to overlap each other, one of said ends extending into the place of said cutaway portion and a pocket formed in the band at the rear thereof, as and for the purpose specified.

In testimony whereof I have affixed my signature.

JAMES LAYDEN.
